(57) **CLAIM**

The ornamental design for a poker faucet as shown and described.

DESCRIPTION

FIG. 1 is an isometric view of a poker faucet showing my new design;

FIG. 2 is a front elevational view thereof;

FIG. 3 is a top plan view thereof;

FIG. 4 is a bottom plan view thereof;

FIG. 5 is a right elevational view thereof;

FIG. 6 is a left side elevational view thereof; and,

FIG. 7 is a rear elevational view thereof showing my design. The elements in broken lines represent components of the poker faucet that form no part of the claimed design.
